FIREARM

George Norman Albree, Winchester, Mass.

Application May 9, 1940, Serial No. 334,147

6 Claims. (Cl. 42—69)

This invention relates to firearms and has been shown as applied to shoulder arms, although I wish to state that certain features of the invention are equally applicable to firearms of other types.

One feature of my invention relates to the firing mechanism, which is so constructed that the release of the firing pin is controlled by a toggle device constructed so that when it is straightened it locks the firing pin in cocked position, the breaking of the toggle by the actuation of the trigger operating to release the firing pin.

An advantage of this construction is that the toggle not only provides a lock for holding the firing pin in cocked position but because of the principle on which a toggle lever operates a relatively small force is required to break the toggle from its straightened position and thereby release the firing pin.

Another feature of my invention relates to electrically actuated means for releasing the firing pin.

According to this feature of the invention, the sear which normally holds the firing pin in cocked position is rendered operative to release the firing pin by a suitable magnet which can be energized by the actuation of the trigger.

With this construction, the trigger is relieved of any work in connection with moving the sear, and its only function is to close the circuit of the magnet, the operation of releasing the sear being done entirely by the magnet. This makes it possible to provide a firing mechanism with a perfectly smooth even trigger take-up which is free from any jolt or jar at the let-off that might disturb the alignment of sights.

A further advantage incident to this construction is that if when aiming the weapon, the sights go off the target at partial take-up of the trigger it is not necessary to hold the slack already taken up while the sights are being brought back onto the target because a partial take-up of the trigger has no effect on the sear, said sear only being actuated when the trigger has been given its full take-up.

This feature of an electrically actuated means for releasing the firing pin is especially adapted to shoulder arms in which the breech end of the barrel is situated at or closely adjacent to the butt of the stock because the sole function of the trigger is to close the circuit of the electrically actuated firing mechanism, and hence no difficulty is encountered by reason of the fact

that the trigger is placed well in front of the gun's "action."

A further object of the invention is to provide an electrically actuated firing mechanism which is constructed so that while the actuation of the trigger results in closing the circuit and thus energizing the magnet which releases the firing pin, yet the forward movement of the firing pin serves to de-energize the magnet again, even though the pressure may be retained upon the trigger.

A further object of the invention is to provide a novel construction by which the toggle device that controls the release of the firing pin is actuated by means of the magnet.

A further object of the invention is to provide an electrically actuated firing mechanism for firearms in which the magnet can be energized either from a source of electricity carried in the stock of the firearm or from some outside source of electricity.

Other objects of the invention are to improve generally electrically actuated firing mechanism in various particulars hereinafter set forth.

25 In the drawings, wherein I have illustrated a selected embodiment of my invention:

Fig. 1 is a side view of a shoulder arm having my improvements embodied therein.

Fig. 2 is an enlarged longitudinal section through the butt end portion of the firearm shown in Fig. 1, said figure illustrating a firing mechanism with the firing pin in cocked position.

Fig. 3 is a fragmentary sectional view illustrating the action of the device in releasing the firing pin.

35 Fig. 4 is a section on the line 4—4, Fig. 2.

Fig. 5 is a fragmentary sectional view showing the manner of connecting the firing mechanism to an outside source of electricity.

40 Fig. 6 is a fragmentary view illustrating the application of the invention to a different type of action from that shown in Figs. 2 and 3.

Fig. 7 is a sectional view of the solenoid which controls the release of the firing pin.

45 Fig. 8 is a fragmentary view illustrating a different embodiment of the invention.

In the drawings, 1 indicates the barrel of a shoulder arm and 2 the stock. The firearm herein shown is of the familiar single shot breech-loading type, and 3 indicates the bolt which is provided with the usual handle 4 by which it may be manipulated. Associated with the bolt is the usual firing pin 5 by which the cartridge 6 is detonated, said firing pin having the shank 7 which is acted upon by a suitable spring 8 that

gives the firing pin its operative movement when it is released. The firing pin is held in its cocked or retracted position by a sear element 9 as usual in firearms, said sear element being pivoted to the barrel at 10 and having a lateral projection 11 adapted to engage a shoulder 12 formed on the shank 7 of the firing pin. When the sear is in the raised position, shown in Fig. 2, it will hold the firing pin in a cocked position against the action of the spring 8, but when the sear is swung downwardly about its pivot 10 to withdraw the projection 11 from the shoulder 12, then the firing pin is released and it is given its operative movement by the action of the spring 8. 91 are blocks or supports secured to the barrel and which provide a mounting for a telescope sight.

The parts thus far described are such as are commonly found in firearms of this type.

In the firearm illustrated, the barrel 1 is so mounted on the stock 2 that the receiver or breech end 80 of the barrel is closely adjacent the butt end of the stock, and the stock 2 is constructed to extend substantially the full length of the barrel. With this construction, the over-all length of the firearm may be considerably reduced without shortening the length of the barrel because such over-all length is approximately the same as the combined length of the receiver and the barrel. The shoulder arm is provided with the usual trigger 31, and in my improved gun, the trigger is located in a trigger opening 82 that is cut in the stock 2. The stock has a progressively increasing vertical dimension from its front end to a point in the rear of the trigger and the lower wall 81 of the trigger opening constitutes a trigger guard which is flush with the lower face of the stock.

In the construction shown, the trigger 31 is pivotally mounted on a pin 90 which is secured to the under side of the barrel 1, the upper end of the trigger having a recess to receive the pin which is of a depth to embrace slightly more than one half the circumference of the pin. In using a gun of this type in the conventional way, the face of the shooter will lie alongside the barrel in front of the bolt instead of being situated behind the barrel, as is the case when operating an ordinary shoulder arm. I regard this as of considerable importance because of the safety factor involved. With my improved gun, if the bolt should accidentally give way during use, said bolt would pass harmlessly over the shoulder of the gunner instead of striking him in the face, a thing which might happen where the face of the gunner is located behind the breech end of the barrel, as is the case when using the ordinary shoulder arm. Furthermore, since the face of the gunner is in front of the bolt, there is no danger of the gunner being injured by the escape of gases around the bolt due to a blown primer or any other cause.

This construction has the further advantage that the center of gravity of the shoulder arm is located nearer to the butt end than in the ordinary shoulder arm, which makes it easier for the gunner to manipulate the gun, especially when aiming at a moving target.

The reason for this is because in the gun herein illustrated, the center of gravity of the firearm is located well in the rear of the portion of the stock which is normally grasped by the extended arm of the gunner and is, therefore, located between the gunner's extended hand and his shoulder. Because of this fact, the retard-

ing effect of the inertia of the gun on any quick movements of the gunner in following a moving target is greatly reduced, and this makes it that much easier for the gunner to manipulate the gun when following a moving target.

The barrel is secured to the stock by means of the bolt 88 which extends through the stock at the butt end and has screw-threaded engagement with a supporting block 17 which, in turn, is secured to the under side of the barrel by attaching screws 18. This single bolt 88 is sufficient to hold the barrel to the stock, but if desired, additional securing means may be employed between the trigger and the muzzle of the barrel.

One feature of my invention relates to a novel construction by which a toggle device is used for controlling the release of the firing pin, said toggle device being so constructed that when it is straightened, it holds the firing pin locked in its cocked position, means separate from the trigger being provided whereby when the trigger is actuated, the toggle will be "broken," thereby releasing the firing pin. In the construction herein illustrated, this toggle device comprises the toggle members 13 and 14 which are pivotally connected at 26, the toggle member 13 being pivoted at 89 to the free end of the sear 9 and the toggle member 14 being pivotally connected at 15 to an extension 16 formed on the block 17. The construction is such that when the toggle device is straightened with the arms 13 and 14 thereof in line with each other, as shown in Fig. 1, the sear will be in its operative position with its projection 11 engaging the shoulder 12. The block 17 is formed with the abutment face 19 against which the toggle arm 13 rests when the toggle device is thus straightened, so that the toggle device can "break" in one direction only. The toggle device might thus be described as a one-way toggle device.

The toggle arm 14 is acted on by a light spring 20 which tends to straighten the toggle, said spring thus normally holding the toggle in its straightened position, as shown in Fig. 2.

This toggle device not only serves as a means for giving the sear 9 its movement into and out of operative position but it also serves to lock the sear in its operative position and to prevent any accidental release of the firing pin.

When the toggle is in straightened condition, shown in Fig. 2, with the toggle arm 13 held against the abutment 19 by the spring 20, said toggle acts as a rigid bar which locks the sear in its operative position. This toggle will thus function as a lock for the sear.

Means are provided whereby when the trigger 31 is actuated, the toggle device 13, 14 will be "broken," thereby swinging the sear 9 downwardly into a position to release the firing pin, as illustrated in Fig. 3.

While various means may be employed for breaking the toggle when the trigger is actuated, I have herein illustrated for this purpose a magnet and have provided means for energizing the magnet when the trigger 31 is actuated.

Various types of magnets are suitable for this purpose, but I have chosen herein to illustrate a magnet of the solenoid type, partly because the solenoid type permits a greater range of movement of the armature.

The solenoid is shown at 22 and is illustrated as being supported on posts 23 that are secured to the block 17. The armature or core 24 of the solenoid is connected by a link 25 to the center joint 26 of the toggle device. When the solenoid

is de-energized and the toggle is straightened, the end of the core 24 will be projected beyond the winding of the solenoid. When the solenoid is energized, the core 24 is drawn into the latter, thereby "breaking" the toggle, as shown in Fig. 3, and releasing the firing pin.

The solenoid is constructed so that the core will have sufficient movement not only to release the firing pin but to withdraw the projection 11 of the sear sufficiently from the barrel to permit the bolt 3 to be removed. When the solenoid is de-energized, the spring 20 will tend to straighten the toggle 14. Such straightening, however, will be prevented so long as the firing pin is in its forward position, shown in Fig. 3, and it is only permitted after the firing pin has been withdrawn to its cocked position, shown in Fig. 2, in which the shoulder 12 of the firing pin has been retracted rearwardly beyond the projection 11 of the sear.

The toggle construction for actuating the sear has the advantage that when the toggle is straightened, a relatively small force is required to break the toggle and conversely, when the solenoid is de-energized, a relatively light spring 20 will be sufficient to straighten the toggle. This is in accordance with the following well-known formula for a toggle lever action:

$$R:P = \cos a : 2 \times \sin a$$

in which R is the resistance to the straightening movement of the toggle lever, P is the power applied to the joint of the toggle lever and a is the angle which the toggle elements make at any time to the longitudinal central line of the straightened toggle.

While the above formula is generally used in connection with the operation of straightening the toggle, yet it is believed that it is equally applicable to the reverse action of breaking the toggle device.

In applying this formula to the construction herein shown, and assuming, for instance, that a pull of two pounds on the end of the sear 9 is necessary to move it sufficiently to release the firing pin, the pulling force required to be applied to the joint 26 of the toggle to move the sear downwardly can be readily calculated for different angular positions of the toggle arms 13 and 14. When, for illustration, the toggle arms 13 and 14 have an angular position of $0^\circ, 15'$ to a line joining the pivots 89 and 15, then substituting these known quantities in the above formula, we obtain the following result:

$$2:P = .99999 (\cos \text{ angle of } 15') : 2 \times .00436$$

$$(\sin \text{ angle of } 15')$$

Solving this equation, it is found that P equals .01744 lb.

It will be evident that as the angle a increases, the value of "P" in the above formula will increase, and as the angle a decreases, the value of "P" will decrease. Hence a relatively small pulling force applied to the joint 26 will be sufficient to break the straightened toggle and actuate the same, because of which it is possible to use a relatively small magnet operating under a low voltage and involving small current consumption to actuate the sear and thus release the firing pin.

I have illustrated herein a rubber buffer element 27 situated within the solenoid and adapted to be engaged by the core 24 when it is moved inwardly. This buffer element not only limits the

inward movement of the core but also cushions such movement.

The solenoid may be energized from any suitable source of electricity, and in the case of a shoulder arm, it is satisfactory to employ a battery in the form of dry cells 28 which may be conveniently located in a pocket or chamber 29 formed in the butt end of the stock. The usual butt plate 30 is shown as having a door portion 79 pivoted thereto at 78, said door, when opened, giving access to the chamber 29 and to the batteries therein, so that battery cells may be removed from the chamber or replaced therein in much the same way that battery cells are removed from or replaced in a flash light.

Means are provided whereby when the trigger 31 is actuated, the circuit connecting the battery 28 with the solenoid 21 will be closed, thereby energizing the solenoid, and in the preferred embodiment of my invention, means are provided for de-energizing the solenoid when the firing pin is released.

The switch which is operated by the trigger for closing the solenoid circuit and thus energizing the solenoid comprises the two contact members 32, and 33, which are carried by a block 34 of insulating material that is secured to the supporting block 17. The contact 33 is a spring contact adapted to be moved into and out of engagement with the contact 32, but the resilience of the contact 33 normally holds it separated from the contact 32.

For actuating the contact 33, there is provided a push rod 35, one end of which operates in an aperture 36 with which the block 34 is provided, and the other end of which is connected to the trigger 31. The end of the push rod 35 which engages the contact 36 will preferably be provided with insulation 37 to prevent any short-circuiting.

In order to provide a suitable resistance for the trigger movement, I have employed a spring 38 which encircles the push rod 35 and is confined between the block 34 and set nuts 39 that are screw-threaded to the push rod. The adjustability of the nuts 39 provides for adjusting the trigger resistance to any desired point.

The switch which is opened to de-energize the solenoid when the firing pin is released comprises the two contacts 40 and 41 which are mounted on the block 42 of insulating material that is, in turn, secured to the supporting block 17. The contact 40 is a spring contact but it is held closed against the contact 41 as shown in Fig. 2 by the bolt stop 45 of the firing pin when the latter is in cocked position. These contacts 40 and 41 are located in an opening 43 formed in the under side of the receiver 1. The contact 40 is extended at its end and is provided with the rounded portion 44 of insulating material that is situated to be engaged by the bolt stop 45 when said firing pin is in cocked position, as shown in Fig. 2. The engagement of the bolt stop 45 with the contact 40 holds it in engagement with the contact 41, thereby closing the circuit at this point. When the solenoid 21 is energized thereby to release the firing pin, the forward movement of the latter will carry the bolt stop 45 off from the rounded end 44 of the contact 40, thereby allowing said contact to spring away from the contact 41 with the result that the solenoid circuit will be instantly opened or broken at this point.

The solenoid circuit comprises a wire connection 46 which leads from the solenoid either to

the battery 28 or to an outside source of current supply, a wire connection 47 which leads from the solenoid to the contact 41, a wire connection 48 leading from the contact 40 to the contact 33 and another wire connection 49 leading from the contact 32 either to the battery 28 or to an outside source of electricity.

The battery 28 is shown as having two battery leads 50 and 51 (shown in dot-and-dash lines), one of which, the battery lead 50, connects to the wire 46, as shown at 52. The other battery lead 51 leads to a contact 53 of a jack switch mounted in a recess 55 with which the stock 20 is provided, the other contact 54 of said jack switch being connected to the circuit wire 49. The purpose of the jack switch is to provide for energizing the solenoid from an outside source of electricity, as will be presently described, instead of from the battery 28, and without involving any change in the operating means.

When the firing pin is in cocked position, as shown in Fig. 2, the switch contacts 40 and 41 will be closed, but so long as the trigger is in its forward position, the solenoid circuit will be opened at the contacts 32, 33.

When, however, the trigger 31 is actuated, the backward movement thereof will operate through the push rod 35 to close the contacts 32, 33, as shown in Fig. 3, and such action will close the solenoid circuit from the battery, thereby energizing the solenoid 22. The energization of the solenoid causes its core 24 to be drawn inwardly, thereby breaking the toggle joint 13, 14, and swinging the sear 9 downwardly to release the firing pin, as shown in Fig. 3. The forward movement of the firing pin carries the projection 45 off from the rounded end 44 of the contact 40, whereby the resiliency of the contact 40 will separate it from the contact 41, thereby opening the solenoid circuit and causing the solenoid to be de-energized. The solenoid circuit, therefore, is closed only for the briefest period of time, even though the contacts 32, 33 are held closed by continuing pressure applied to the trigger. The battery, therefore, will be subjected to minimum drain. Ordinary flashlight batteries can be successfully used for energizing the solenoid 22.

When the bolt is retracted for inserting a fresh cartridge and for cocking the firearm, the solenoid circuit will be closed again at the contacts 40, 41, by the engagement of the bolt stop 45 with the rounded end 44 of the resilient contact 40, thus putting the solenoid circuit again in condition to be closed for energizing the solenoid by the actuation of the trigger 31.

Figs. 2 and 3 illustrate my invention as applied to one type of breech-loading shoulder arm, but I desire to state that the invention is equally applicable to other well-known types. In Fig. 6, I have illustrated how the invention might be applied to the type of action embodied in the Winchester model 70 rifle, in which 99 indicates a portion of the firing pin and 98 indicates the sear which is pivotally mounted at 97 and is adapted to engage the shoulder 96 of the firing pin to retain the latter in cocked position. The sear is acted on by a spring 100 which tends normally to swing it into its operative position, and said sear is held in such position by a retaining lever 95 which is pivotally mounted at 94, said lever having a shoulder 93 which engages the sear and holds the latter in the position shown in the drawings in Fig. 6. The above parts are

such as are found in the well-known Winchester model 70.

In applying my invention to this construction, I connect the arm 13a of the toggle lever device 5 to the retaining member 95, the other arm 14a of the toggle device being pivotally mounted at 15a to a fixed support 16a. 22a indicates a magnet, the armature 24a of which is secured to the toggle device 13a, 14a at the joint thereof. 10 The toggle device is acted on by the light spring 20a which tends to hold it in straightened condition shown in Fig. 6, with the toggle arm 13a resting against the abutment 19a.

When the magnet 22a is energized, the armature 24a is pulled rearwardly, thereby breaking the toggle device and releasing the sear, the release of which allows the firing pin to move forwardly, as will be understood by those familiar with the above Winchester model.

In this embodiment, the sear 98 will be released by a very small movement of the retaining member 95, which will result from a slight breaking movement of the toggle.

In this embodiment also, the toggle lever, when 25 in straightened condition as shown in Fig. 6, constitutes a lock for the sear which will positively hold the sear in its operative position and thus prevent premature discharge of the gun, even though the gun is dropped or is jarred violently.

I have stated above that my invention involves a construction wherein the current for energizing the solenoid 22 may be taken from an outside source instead of from batteries 28 carried within the stock 2. This is provided for by the use of 30 the jack switch, mounted in the recess 55 and comprising the contacts 53 and 54. This jack switch, which may be of any usual construction, comprises an L-shaped frame member 56 which is secured to a cover plate 57 of insulating material that is secured to the stock by screws 58 and which serves to close the open end of the recess 55. The circuit wire 46 leading to the solenoid is connected to this frame member 56.

The contact member 54 which is a spring or 45 resilient contact, is carried by a plate 59 that is insulated from the frame member 56 and to which the circuit wire 49 is connected.

The contact 53 of this jack switch is carried 50 by a plate 60 which is also insulated from the plate 59 and the frame member 56, and to which the battery lead 51 is connected. When the current for energizing the solenoid 22 is taken from the battery, the complete circuit will comprise the battery lead 51, the plate 60, contact 53, contact 54, plate 59, wire connection 49, contacts 32, 33, wire connection 48, contacts 40, 41, wire connection 47, to the solenoid windings, wire connection 46 and the battery lead 50.

When a current from an outside source is to be used, said current will be brought from any suitable current supply through a two-wire cable 61 (see Fig. 5) having at its end a jack plug 62 adapted to plug through the sleeve 63 carried by the cover plate 57 and which is secured to the L-shaped frame member 56. This jack plug has an end terminal 64 connected to one wire 65 of the two-wire cable 61 and a terminal portion 66 connected to the wire 67 of said two-wire terminal, these two terminal portions 64 and 66 being insulated from each other by insulation 68. When the jack plug is inserted through the sleeve 63, as shown at Fig. 5, the end terminal 64 engages the contact 54 and forces it away from the contact 53, thus opening the battery circuit at this point. The terminal 66, however, which fits

within the sleeve 63 is electrically connected to the frame plate 56 and thus to the wire connection 46 leading from the solenoid. When the jack switch is used, as shown in Fig. 5, the solenoid circuit comprises the wire 65 of the two-wire cable, the terminal contact 64, the contact 54, the plate 59, the wire connection 49, the contacts 32, 33, wire connection 48, contacts 40, 41, wire connection 47, solenoid windings, wire connection 46, the frame plate 56, the terminal portion 66 of the jack plug and the wire 67 of the two-wire cable.

The two-wire cable may be of any length and may be connected to any suitable source of current, either D. C. or A. C. If it is connected to an ordinary lighting circuit, it will be necessary, of course, to employ suitable resistance or a transformer in the circuit to reduce the voltage to that required by the solenoid 21.

When the current for actuating the solenoid is taken from an outside source, the circuit of the battery 28 will be open between the contacts 53, 54, as shown in Fig. 5, and, therefore, it will make no difference whether the battery cells 28 are in the gun or not.

In Fig. 8 I have shown a modified form of the invention in which the initial movement of the trigger serves to relieve the spring pressure on the toggle device, and further movement of the trigger serves to close the switch, thereby to energize the solenoid. Since the spring pressure on the toggle is relieved prior to the energizing of the solenoid, the only work which the solenoid is required to do is to break the toggle, an operation which requires very little force. In Fig. 8, the toggle device, which is similar to that shown in Figs. 2 and 3, comprises a toggle lever 13b, 14b, the toggle element 13b being pivotally connected to the sear element 9b and the toggle member 14b being pivotally connected at 15b to the projection 16b. The solenoid is indicated at 22b, and the core 24b thereof is connected by a link 25b to the toggle in the same manner as illustrated in Fig. 3.

20b indicates the spring which acts on the toggle and normally tends to hold it in straightened position. In this embodiment of the invention, the rod 35b by which the switch contacts 32, 33, are closed has secured thereto an auxiliary rod member or extension 101 which extends forwardly into position to engage the end of the spring 20b, said spring and the end of the rod being properly shaped to have such engagement when the rod 101 moves toward the left, the construction is such that during the initial movement of the trigger and before the rod 35b has been moved sufficiently to close the contacts 32, 33, the rod extension 101 will have engaged the spring 20b and moved the latter backwardly, thus relieving the toggle from its spring pressure.

When the rod 35b has been moved sufficiently to close the contacts 32, 33, thereby energizing the solenoid 22b, the only work which is required of the solenoid is to break the toggle device. Since the spring pressure on the toggle device has been previously relieved, a relatively small force will be required to break the toggle and thus actuate the sear element 9b.

The construction shown in Fig. 8 would make it possible to use smaller batteries 28.

My invention is capable of use with either A. C. or D. C. current.

While I have illustrated my invention as applied to shoulder arms, yet I wish to state that many features of the invention, such as the toggle device for controlling the sear element, and the electrically actuated means for releasing the firing pin, are also applicable to firearms of other types than shoulder arms.

I claim:

1. A firearm having a barrel, a firing pin, means for holding the firing pin in cocked position, an electrically actuated means to release the firing pin, a trigger for rendering said electrically actuated means operative, and means controlled by the firing pin to render the electrically actuated means inoperative when said firing pin is released.

2. A firearm having a barrel, a firing pin, means for holding the firing pin in cocked position, electrically actuated means to release the firing pin, a circuit controlling said electrically actuated means, a trigger, means actuated thereby to close said circuit thereby rendering the electrically actuated means operative, and means controlled by the firing pin for opening the circuit when said firing pin is released.

3. A firearm having a barrel, a spring-actuated firing pin, a sear element for holding the firing pin in cocked position, a magnet for operating the sear to release the firing pin, a circuit for the magnet, said circuit including a normally open switch and a second switch which is held in closed condition by the firing pin when the latter is in cocked position but which is opened when the firing pin is released, a trigger, and means to close the normally open switch by movement of the trigger.

4. A firearm having a barrel, a firing pin, means for holding the firing pin in cocked position, a magnet to actuate said means, thereby to release the firing pin, a trigger, means actuated by the trigger to energize the magnet, and means rendered operative by the operative movement of the firing pin to de-energize the magnet.

5. A firearm having a barrel, a firing pin, means for holding the firing pin in cocked position, a magnet to actuate said means, thereby to release the firing pin, a trigger, means actuated by the trigger to energize the magnet, and means controlled by the firing pin to de-energize the magnet as the firing pin has its operative movement.

6. A firearm having a barrel, a firing pin, a sear for holding the firing pin in cocked position, a trigger, a toggle joint device connected to the sear, said toggle joint device when in straight line, dead center condition holding the sear in its operative position, a stop preventing breaking movement of the straightened toggle joint device in one direction, a magnet, an armature therefor connected to the toggle joint device at the central joint of the toggle and operative to break said toggle joint device when the magnet is energized, and trigger-actuated means to energize the magnet, the straight line condition of the toggle joint device necessitating a minimum pulling force to break it, whereby the sear may be actuated to release the firing pin by a relatively small magnet operating under low voltage.
